DESIGN FOR A CARPENTER'S PLANE

Samuel Oxhandler, Flushing, N. Y., assignor to
Sargent & Company, New Haven, Conn., a cor-
poration of Connecticut

Application December 18, 1943, Serial No. 112,027

Term of patent 3½ years

To all whom it may concern:

Be it known that I, Samuel Oxhandler, a citizen of the United States, residing in Flushing, in the county of Queens and State of New York, have invented a new, original, and ornamental Design for a Carpenter's Plane, of which the following is a specification, reference being had to the accompanying drawing, forming part thereof, in which

Fig. 1 is a side elevational view of a plane em-
bodying my new design;

Fig. 2 is a top plan view of the same;

Fig. 3 is a front end view of the plane; and
Fig. 4 is a rear end view of the plane.

I claim:

The ornamental design for a carpenter's plane,
substantially as shown.

SAMUEL OXHANDLER.
